BOOKHOLDER

Nathan I. Stark, Philadelphia, Pa.

Application January 15, 1931. Serial No. 508,916

9 Claims. (Cl. 45—57)

The invention relates to book-ends, reading-rests and pamphlet and paper holders and more particularly to a combination of one with the other.

5 An important object of the invention is the provision of a book-end that is engageable with the cover boards of a book and adapted to support said book in an open position and at a suitable angle of inclination for reading or copying therefrom.

10 Another object of the invention is the provision of two book-ends that are engageable with each other or to a suitable backing to form an easel stand having a forwardly and upwardly extending shelf on which books and pamphlets may be held up in an open position, said shelf being wide enough to accommodate a ruler or other suitable article for preventing the pages from accidentally turning.

15 Still another object of the invention is the provision of two book-ends that are engageable one with the other to form a U shaped holder which may be used for books, pamphlets, letters and paper.

20 Another important object of the invention is the provision of a reading-rest that may always be handy for immediate use and easily disposed of after reading.

25 A further and important object of the invention is the provision of a book-end that can be manufactured from wire, rounded rod or other suitable material that will be light in weight and without sharp corners or edges to mar the surface upon which it may be placed.

30 A still further object of this invention is the provision of a holder of this character which is extremely simple in construction, thoroughly efficient and which affords an economical device for the purposes intended and which may be manufactured at a minimum cost.

35 With these and other objects in view the invention therefore consists in the subject matter herein described, illustrated in the drawing, and set forth in the appended claims.

40 Referring to the drawing:

Figure 1 is a perspective view of my invention.

Figure 2 is a perspective view thereof assembled to form a U shaped rack or holder for books, pamphlets, letters and paper.

45 Figure 3 is a perspective view of books being held up with the invention used as a book-end.

Figure 4 is a perspective view of the invention assembled to form an easel stand.

50 Figure 5 is a perspective view of a book being held up in an open position by the invention being engaged with the lower portion of the cover boards of said book.

55 Figure 6 is a perspective view of a book being held up in an open position by the invention being engaged with the upper portion of the cover-

boards of said book using the opposite side of the device as shown in Figure 5.

The particular embodiment shown in the drawing for the purpose of illustrating the principles of the invention, comprises a frame, Figure 1, which is preferably constructed from one piece of wire or rounded metal rod having some resiliency and adapted to be formed into a series of bends and joined at O by welding or soldering. A panel member P of binder board or other suitable material and of a thickness equal to the diameter of material used to form said frame, is placed between sides A, B and C and held in place by binding cloth Q or other suitable material wrapped across the faces of said binder-board and around the outside of A and C portions of said frame, said cloth being held to the binder-board by first coating one side thereof with a suitable glue.

60 In Figure 1 the frame is divided into portions and lettered. Portions A—B—C comprise the upright panel side, while the other portions comprise the base or engaging side, said sides being in planes substantially at right angles one to the other.

65 Binder-board P held with binding Q, fills in and re-enforces the panel side and provides a surface for decorations which is useful to the book-end feature of the device.

70 The side of the binder-board P, facing the portions G and K is termed the front side of the device while the other side of the said binder-board is termed the rear side.

75 The front side of the device is attached and held frictionally by inserting the cover-boards of a book parallel with and between portions F—G—H and portion D on one end, and portions J—K—L and portion N on the opposite end of said device. This is best illustrated in the assembly shown in Figure 5; portions F—G—H are on the inside of cover-board 1 while portion D is on the outside, portions J—K—L are on the inside of cover-board 2 and portion N on the outside, the edge of binder-board P is positioned across the binding bracing the cover-boards 1 and 2 in a plane substantially 80 at right angles to the plane occupied by the panel side portions A—B—C.

85 The rear side of the device is attached and held frictionally by assembling portions D—E—F on one side of the cover-boards, portions H—I—J on the opposite side of said cover-boards and portions L—M—N on the same side as portions D—E—F.

90 Figure 6 shows portions D—E—F on the inside of cover-board 3, portions H—I—J on the outside of cover-boards 3 and 4 and spanning the binding thereof while portions L—M—N are on the inside of cover-board 4.

95 On large books having thick cover-boards, a device is placed on each cover-board with por-

tions H—I—J on the inside of said cover-board and portions D—E—F—I—M—N on the outside. The portions G and K being longer than portions E and M allows a thicker cover-board 5 to be held without straining the device or marking the said cover-boards.

In Figure 2, the U shaped holder is formed by dovetailing two similar devices together, portions D—E—F overlap portions L—M—N at 10 either end and portions H—I—J overlap portions H—I—J in the centre. The distance between the panel sides A—B—C may be varied by dovetailing said panel sides A—B—C closer together or farther apart.

15 In Figure 3 the device is shown in use as a book-end; portions A—B—C forms the panel side of the device for holding the books in an upright position by means of some of the said books resting on the portions that are substantially at right angles thereto.

20 The easel stand in Figure 4 is formed by assembling two of the devices together using panel side A—B—C and binder-board P of one of the said devices as a backing. The exposed edge of binder-board P, opposite and parallel with portion B, provides a prop in conjunction with portions D and N.

25 The assembly of the said two devices is as described for the front side, with the exception that the engaging side engages only a part of the panel side used for a backing. Other forms of an easel stand may be constructed by using the cover-boards of a book, a card-board or other suitable sheet material for a backing and 30 assemble two devices thereon in a manner as described.

35 The angle of inclination of a book may be changed by assembling the device or devices on the top or bottom portions of the cover-boards 40 of said book or by constructing a special easel stand of card-board and two devices for placing said book thereon.

45 The angle of inclination of the easel stand shown in Figure 4 may be changed by moving the engaging side up or down on the panel side or backing.

50 An important feature of the easel stand shown in Figure 4, is the forward and upward extending shelf which extends a sufficient distance forward to accommodate an average book in an open position and have sufficient space remaining to accommodate a ruler or other suitable article to prevent the pages of said book from accidentally turning when reading or copying 55 therefrom.

60 By resting portions B, G and K of a device on a table or other flat surface the engaging side of said device will assume a slight angle suitable for holding newspapers, magazines, and single sheets of printed work for reading or copying therefrom.

65 For some purposes it may be practical to construct the supporting side from all wire formed in a series of bends substantially in one plane and substantially at right angles to the engaging side.

70 Many departures and variations may be made from the precise structure herein disclosed without departing from the spirit of my invention, since I claim:

75 1. A book holder comprising a wire frame, a backing of suitable material disposed therein and means for fastening said backing therewith,

said frame comprising an integral piece of wire bent near the middle to form an open loop extending in substantially one plane and having each end bent in the same plane to form outer open loops and thence bent and suitably joined in a single plane substantially at right angles to first said plane and adjacent one end of said loops to form a rectangular support for said backing.

80 2. A pair of book ends, comprising two rigid panel members, each having a side member projecting at a suitable angle therewith, one of the members of one book end being adapted to engage one of the members of the other book end to form an easel stand and one of the unengaged members forming a ledge projecting from the easel stand.

85 3. A bookholder comprising two rigid panel members each having members projecting laterally to one side thereof so that said members of one panel may be engaged with the other panel to form an easel stand, and the like members of the other panel to form a ledge projecting from the easel stand.

90 4. A pair of book ends, each comprising a panel portion and angularly projecting spaced members with substantially equal main and rebent portions, those members of one panel being adapted to mutually interfit with those of the other to serve as book ends, while each panel portion may 100 also independently serve as a book rest, with the spaced members serving to prop the panel portion and their rebent portions serving to engage the book leaves or covers.

95 5. A bookholder comprising a piece of wire describing a closed circuit constituting a panel and further forming a member at a suitable angle to said panel comprising loops and return bends, all the elements of which normally lie in one plane, but certain elements of which are 105 distortable into separate parallel planes.

100 6. A bookholder comprising a substantially rigid frame and at a suitable angle therewith, an integral piece of wire bent near the middle in substantially one plane to form a central loop, 120 said wire having both ends bent in the same plane to form loops adjacent said central loop and said ends terminating in said frame.

115 7. A bookholder comprising a substantially rigid frame, and at a suitable angle therewith, an integral piece of wire bent near the middle in substantially one plane to form an angular central loop, said wire having both ends bent in the same plane to form angular loops adjacent said central loop and said ends terminating in said frame.

120 8. A bookholder comprising a rigid panel member having central and adjacent side members projecting at a suitable angle thereto, said central and adjacent side members lying normally 135 in one plane and having certain portions which are distortable into separate parallel planes.

130 9. A pair of book ends, each comprising a rigid panel member and an angularly projecting member with main and rebent portions, the projecting member of one panel adapted to mutually interfit with the other to serve as book ends, while the panel members may also serve to prop books, with the main and rebent portions serving to engage the book covers of said books and hold said panel members in propping position thereon.

NATHAN I. STARK.
